Clarence J. Dorn and Joseph L. Jaegly, Toledo,
Ohio

Application July 3, 1934, Serial No. 52,453

Term of patent 3½ years

To all whom it may concern:

Be it known that we, CLARENCE J. DORN and JOSEPH L. JAEGLY, citizens of the United States, both residing at Toledo, in the county of Lucas and State of Ohio, have invented a new, original, and ornamental Design for a Combined Lamp Lens and Frame Therefor, of which the following is a specification, reference being had to the accompanying drawing, forming a part thereof.

Fig. 1 is a front view of the combined lamp

lens and frame therefor. Fig. 2 is a side view of the lamp lens and frame therefor.

We claim:

The ornamental design for a combined lamp lens and frame therefor as shown.

In witness whereof we have hereunto signed our names to this specification.

CLARENCE J. DORN.
JOSEPH L. JAEGLY.
